UNITED STATES PATENT OFFICE.

JAMES K. DELANO, OF NEW YORK, N. Y.

AUTOMATIC CUT-OUT APPARATUS.

1,371,990.

Specification of Letters Patent. Patented Mar. 15, 1921.

Application filed February 25, 1918. Serial No. 219,097.

To all whom it may concern:

Be it known that I, JAMES K. DELANO, a citizen of the United States, residing at New York, in the county of New York and State 5 of New York, have invented certain new and useful Improvements in Automatic Cut-Out Apparatus; and I do hereby declare the following to be a full, clear, and exact description of the invention, such as will enable 10 others skilled in the art to which it appertains to make and use the same.

This invention relates to automatic cut-out apparatus, and particularly to apparatus of this general character for employment 15 with internal combustion engines in which a dynamo electric machine is in driving connection with an internal combustion engine or other prime mover and is arranged to control and actuate through the rotation 20 of its armature shaft means for opening and closing an electric circuit, such as an ignition or charging circuit, depending upon the direction in which said armature shaft rotates.

In electrical systems commonly used on 25 automobiles and other motor vehicles driven by internal combustion engines, a storage battery and its connecting mains are employed to furnish current for ignition, lighting, etc. In the case of ignition, the system 30 includes interrupter mechanism in circuit with the battery, whereby the making and breaking of a primary circuit induces high tension oscillations in a secondary circuit of such character as to furnish suitable 35 sparking current at the spark plugs of the engine. Ordinarily a manually operated switch is provided to disconnect the ignition system from the battery when the vehicle 40 is at rest, but if the operator neglects to so disconnect the ignition system, and if the engine happens to stop in such position that the contacts of the interrupter mechanism 45 are in circuit-closing position, the battery may be discharged through the primary ignition circuit, thus wasting current and causing the battery to deteriorate. Again, where a storage battery forms a part of the equipment of a motor vehicle driven by an 50 internal combustion engine or by a steam engine, the battery is usually arranged to be charged during the running of the vehicle by means of a suitable generator driven from the engine shaft. When the vehicle stops, the battery mains would be short-circuited 55 through the low resistance armature of the generator, unless switch means or a cut-out

device of some kind, either manually or automatically operable, were actuated to disconnect the generator from the battery. Unless the battery were thus disconnected from the 60 generator when the vehicle is at rest, the battery would of course discharge through the generator, resulting not only in loss of current but also in damage both to the battery and the generator.

Automatic cut-out means for breaking ignition circuits, charging circuits, etc., in storage battery systems of the character mentioned, have been proposed heretofore and have gone into use to a certain extent. 70 The principal object of the present invention is to provide improved and simplified means for accomplishing this general result, and also to provide an arrangement of which the operation is especially effective and dependable. Another object of the invention is to combine cut-out means of this general character with ignition mechanism in a compact unit adapted for connection to a driven shaft. Another object is to combine such 80 cut-out means with a dynamo electric machine in a substantially unitary construction. A still further object is to combine cut-out means, ignition mechanism and a dynamo electric machine in a complete unitary construction adapted for convenient 85 driving connection to the shaft of the internal combustion engine or other prime mover, the combination affording a very compact construction which has certain important 90 practical advantages such as simplicity, convenience of installation, and durability. The dynamo electric machine may be either a generator, or a dynamo motor.

In the present invention, which is more 95 particularly adapted for use with an internal combustion engine, advantage is taken of the fact that when a gas engine stops, its shaft rocks back more or less, usually to a position where the engine pistons are practically in line, this rocking back being due to the compression in the cylinders. In apparatus constructed in accordance with my invention, therefore, circuit-opening-and-closing mechanism is so mounted on a shaft 100 which is adapted for driving connection directly or indirectly with the engine shaft, that upon rocking back of the engine after it stops, said mechanism is actuated by reverse rotation of its supporting shaft to 105 place said mechanism in circuit-opening position or phase. On the other hand, when

the engine is running and said shaft is consequently rotating in its normal direction, said mechanism is thereby maintained in circuit-closing position or phase. Said 5 mechanism is adapted for connection in a circuit which includes a storage battery and which is of such character that unless automatically operating cut-out means of some kind were provided to break the circuit 10 upon stopping of the engine, it would be possible for the battery to discharge through the circuit. In one embodiment of the invention, the circuit opening and closing mechanism, or cut-out mechanism, 15 is so associated structurally with a dynamo electric machine as to be housed therewith in a compact structural unit; and in an embodiment of the invention especially desirable where the cut-out mechanism controls 20 an ignition circuit, the principal moving parts of the ignition system are associated with the cut-out mechanism in a structural unit which is especially adapted for combination with a dynamo electric machine in 25 a larger unit, but which may be driven from the crank shaft or other moving part of the engine, where desirable.

With the foregoing general objects in view, as well as others which will appear 30 hereinafter, the invention comprises both broadly and specifically the constructions shown in the accompanying drawings and more particularly pointed out in the claims. It is to be understood, however, that the 35 specific constructions here illustrated are merely typical of apparatus within the scope of the invention and embodying its broad principles, and that the invention is not restricted thereto.

40 In the drawings, which are more or less diagrammatic,

Figure 1 is a sectional view of apparatus constructed in accordance with the invention, parts being shown in elevation;

45 Fig. 2 is a fragmentary view in perspective on a larger scale further illustrating the slip ring arrangement shown in Fig. 1;

Fig. 3 is a section, partly in elevation, of another form which the invention may take; 50 and

Fig. 4 is a section on the line 4-4 of Fig. 3.

Referring first to the apparatus illustrated in Fig. 1, 10 indicates generally a dynamo electric machine, in this instance a lighting generator, whose armature shaft 11 is geared through pinions 12 and 13, to the crank shaft 14 of an internal combustion engine, indicated generally at 15. As is usual in 60 installations of this character, the gearing between the engine and the generator is a speed multiplying connection, the pinion 13 having, for example, twice as many teeth as the pinion 12, and the armature shaft of 65 the generator consequently having a rota-

tional speed twice as great as that of the engine shaft. The lighting generator is enclosed in suitable housing, as shown, in which the armature shaft is journaled at 16 and 17. The armature shaft is extended at 70 17, and the housing has a corresponding extension 18 to provide an inclosed space within which is mounted automatic cut-out mechanism. This mechanism consists of two relatively movable contact members so 75 arranged as to make conducting contact during normal rotation of the armature shaft, that is, while the engine is operating, but to break such conducting contact upon reverse rotation of the armature shaft. In 80 the present example, these contact members take the form of metal slip rings 19 and 20, carried respectively by insulating bushings 21 and 22, bushing 21 being fixed to the armature shaft by a key 23 or otherwise, while 85 bushing 22 is loose on the shaft, that is to say, it can turn on the shaft. The slip rings are spaced apart, in any convenient manner, the hub 22^a of bushing 22 performing this function in the particular construction here 90 illustrated. Some means for electrically bridging the gap between the two slip rings under proper operating conditions is provided, and this means may take any convenient form. In the present instance, slip 95 ring 19 carries a projecting pin 24, which, upon rotation of the armature shaft in the normal operating direction, is adapted to engage a similar pin 25 carried by a slip ring 20, and thus to electrically connect said 100 slip rings. After pin 24 has thus made contact with pin 25, continued rotation of the armature shaft causes slip ring 19 to carry slip ring 20 along with it, the two slip rings thus rotating together with the shaft under 105 normal running conditions. Brushes 26 and 27 bear on slip rings 19 and 20, respectively, and, together with the exterior terminals 28 and 29, adapt said slip rings for connection in an electrical circuit. In the particular 110 embodiment of the invention shown in Fig. 1, such circuit includes a storage battery 30, connected on one side to brush 31 of the generator, and on the other to terminal 28, terminal 29 being connected to the other 115 brush 32, as shown. At 33 is indicated a regulating winding of some kind for preventing overcharging the battery at high speeds. It may take the form of a bucking field winding in the generator, for example. 120 A lighting system 34, or other current-consuming device, may be supplied from the battery mains. Upon stopping of the engine, either accidentally or by the intention of the driver, the engine shaft will rock 125 back to a greater or less extent as before explained, and this reverse rotation of the crank shaft will be transmitted to the armature shaft 17, whereupon the slip ring 19, being compelled to rotate with the shaft, 130

will also reverse its direction of rotation. Slip ring 20, on the other hand having no positive driving connection with the armature shaft and being restrained to some extent by the friction of brush 27, supplemented if desired by the additional braking action of a spring-pressed brake member 36, will not participate in this reverse rotation. As a consequence, contacts 24 and 25 will thereupon separate and the battery circuit will be broken.

Should the rocking back of the engine shaft be sufficient to produce reverse rotation of the armature shaft for a full revolution, the pins 24 and 25 would again be brought into contact unless means were provided to prevent this. In the present example, restoration of the broken circuit in this manner is prevented by means of an insulated pin 37 which is arranged to be engaged by pin 24 if the reverse rotation is sufficiently great, thus preventing the possibility of the circuit being closed except upon rotation of the armature shaft in the normal direction.

It will be noted that where there is a speed multiplying driving connection between the dynamo electric machine and the engine crank shaft, as in the present instance, the rocking back of the engine shaft is multiplied in the reverse rotation of the armature shaft, in this case doubled. The effect of this is to render the cut-out device much more sensitive in its operation than it would be if it were mounted directly on the engine shaft.

In the apparatus of Figs. 3 and 4, the same general principles of operation are employed, but in this instance the cut-out mechanism and the interrupting and distributing devices are mounted in a special housing located at one end of the dynamo electric machine. This arrangement is particularly advantageous for the reason, among others, that the necessary connecting leads can be very materially shortened; while the structural combination of the several parts in a unitary device of this character greatly simplifies construction and makes for increased convenience in mounting the parts of the electrical system on a motor vehicle. In this form of apparatus, an extension 39 of the housing of the dynamo electric machine accommodates the extension 40 of the armature shaft, to which is appropriately geared the vertical shaft 41, driving the cam 42 of a timer or interrupter device, and distributor arm 43, both carried by the upper end of said shaft and inclosed in a suitable housing 44. Also carried by the vertical timer and distributor shaft 41, and located within the housing 44, is automatic ignition cut-out mechanism operable in a manner analogous to that characterizing the cut-out device already described in connec-

tion with the apparatus of Fig. 1. In this instance the cut-out mechanism comprises a conducting pin 45 secured to rotate with the distributor shaft and to make contact with a conducting pin 46 carried by slip ring 47, 70 said slip ring being loosely mounted upon the distributor shaft 41 through the agency of an insulating bushing 48. A brush 49 bears upon the slip ring and has an exterior connecting terminal 50.

When the engine is running, the distributor shaft 41 is rotated in such direction that the contact pin 45 engages contact pin 46, the slip ring 47 being thereby caused to rotate with the distributor shaft. Under these conditions, the primary circuit of the ignition system is closed, assuming of course that the hand switch 35 is closed, and the path of the current may be traced as follows: from the transformer primary to terminal 51, through interrupter contacts 52 and pivoted interrupter arm 53, to terminal 54; thence by way of terminal 50, slip ring 47 and contact pin 46, to contact pin 45, and finally to ground (generator frame) through distributor shaft 41 and, optionally, a spring pressed ground contact 55. The other side of the storage battery 56 is grounded to the frame of the dynamo electric machine as indicated at 57, thus completing the circuit. 95 The high tension current goes to the central terminal 58, from which it is distributed by rotating arm 43 to the several spark plugs through leads from terminals 59, with which terminals arm 43 makes contact successively 100 as it rotates. When the engine stops, the rocking back of the crank shaft will cause reverse rotation of the armature shaft 40, with corresponding reverse rotation of the distributor shaft 41. Pin 45 will accordingly be carried away from pin 46, since the slip ring 47 is loose on the distributor shaft and is frictionally held by the pressure of brush 49, or otherwise, from participating in the reverse rotation. The ignition circuit 105 will, therefore, be broken and the possibility of the battery discharging through the closed interrupter contacts, should they happen to be left in this position when the engine stops, is thereby eliminated. If the reverse rotation of shaft 41 is sufficiently 110 great, the pin 45 strikes insulating pin 57, secured to slip ring 47 or to its insulating bushing, further movement of the pin in this direction compelling slip ring 47 to turn 115 also, and closing of the circuit by reverse rotation being thus prevented. The connection between the interrupter arm and cut-out device is here shown as outside the housing, but it may of course be inside. Moreover the arrangement may be such that they are connected to opposite sides of the battery instead of as here shown. It is to be understood also that the housing means may provide separate chambers for the timing 120 125 130

and distributing mechanism on the one hand and the cut-out mechanism on the other, instead of a single chamber, as in the construction of Fig. 3.

5. The battery circuit is here shown as provided with any usual or suitable cut-out device indicated conventionally at 60. It is obvious, however, that an additional rock-back cut-out device, like either of those hereinbefore described could be mounted upon or geared to the armature shaft to take the place of cut-out 60.

While the embodiments of the invention here illustrated show the employment of the cut-out mechanism with charging and ignition circuits, it is evident that the said mechanism may be used similarly in connection with any other circuit where there is any possibility that stopping of the prime mover may leave the circuit in condition for discharging the battery.

What I claim is:

1. In apparatus of the class described, the combination, with a prime mover, of a dynamo electric machine, a speed-multiplying drive connection between said dynamo and prime mover, a storage battery, and circuit opening and closing means structurally associated with said dynamo electric machine and in circuit with said battery and arranged to be actuated by said shaft to close or to open the circuit, depending upon the direction of shaft rotation.

2. In apparatus of the class described, the combination with a dynamo electric machine having an armature shaft adapted for driving connection to an internal combustion engine, of a housing, circuit opening and closing means mounted within said housing and arranged to be actuated by rotation of said shaft in one direction to maintain a circuit closed, and by reverse rotation of said shaft to open such circuit.

3. In apparatus of the class described, the combination, with a dynamo electric machine having an armature shaft adapted for driving connection to an internal combustion engine, of circuit opening and closing means structurally associated with said machine and arranged to be actuated by said shaft to close or to open a circuit, depending upon the direction of shaft rotation.

4. In apparatus of the class described, the combination, with a dynamo electric machine having a suitable armature shaft, of a contact device fixed to said shaft for rotation therewith, and a coöperating contact device mounted on said shaft and movable with respect to the first contact device, both contact devices being adapted for connection in an electric circuit, the arrangement being such that upon rotation of said shaft in one direction said contact devices are in circuit-closing position, but upon reverse rotation of said shaft are in circuit-opening position.

5. In apparatus of the class described, the combination, with a dynamo electric machine having a suitable armature shaft, of a pair of coöperating contact members, of which one is positively driven by said shaft, 70 while the other has a loose connection thereto, and means adapting said contact members for connection in an electric circuit, said members coöperating to close such circuit upon rotation of said shaft in one direction 75 and to open said circuit upon reverse rotation of said shaft.

6. In apparatus of the character described, the combination with a dynamo electric machine having an armature shaft adapted for 80 driving connection to an internal combustion engine, of housing means into which said armature shaft extends, a circuit opening and closing device in said housing means connected to said shaft and controlled there- 85 by, and a battery ignition circuit for the engine comprising interrupter mechanism, said opening and closing device being included in said circuit and being arranged for actuation by said armature shaft to 90 maintain the circuit closed when the armature shaft is rotating in its normal direction, and to open said circuit upon reverse rotation of the shaft.

7. The combination, with a dynamo elec- 95 tric machine having an extended armature shaft and a suitable housing, of battery ignition mechanism supported by said housing and having a driving connection with said shaft and ignition cut-out means comprising 100 a pair of relatively movable contact members in circuit with said ignition mechanism and operable by rotation of said shaft to make or break the circuit depending upon the direction of shaft rotation. 105

8. In apparatus of the class described, the combination, with a rotatable shaft, of a contact device fixed to said shaft for rotation therewith, and a slip ring loosely mounted on said shaft and provided with 110 contact means arranged to coöperate with said contact device in circuit-closing phase when said shaft rotates in one direction, and to separate from said contact device when said shaft rotates in the reverse direction, 115 and a brush bearing on said slip ring to adapt the same for connection in a circuit, said contact device being also adapted for connection in such circuit.

9. In apparatus of the class described, 120 the combination, with a rotatable shaft, of a pair of slip rings, one fixed to said shaft and the other loose thereon, said slip rings being arranged to make conducting contact during rotation of said shaft in one direction, but to break such contact upon reversal of the shaft, and brushes bearing on said slip rings and adapted to connect the same in a circuit. 125

10. In apparatus of the class described, 130

the combination, with a rotatable shaft, of a pair of slip rings, one fixed to said shaft and the other loose thereon, and means whereby rotation of the shaft in one direction connects said slip rings electrically and 5 compels rotational movement of the frictionally held slip ring in company with the

fixed ring, while rotation of said shaft in the reverse direction disconnects said slip rings electrically.

10

In testimony whereof I hereunto affix my signature.

JAMES K. DELANO.
